STANLEY W. NICHOLSON, OF TOLEDO, OHIO, ASSIGNOR TO THE DURA COMPANY, OF TOLEDO, OHIO, A CORPORATION OF DELAWARE.

LOCK FOR WINDOW REGULATORS.

Application filed March 23, 1926. Serial No. 96,818.

The invention relates to locks and refers more particularly to locks for use in window regulators to hold the windows in their various positions of adjustment. One of the objects of the invention is to provide a lock which is so constructed that it may be cheaply manufactured. Another object is to provide a unitary structure including the lock and driving and driven members to facilitate mounting.

With these as well as other objects in view, the invention resides in the novel features of construction and combinations and arrangements of parts as more fully herein-after set forth.

In the drawings:—

Figure 1 is an interior side elevation of a vehicle door, partly broken away, and showing a window having a lock embodying my invention;

Figure 2 is an enlarged vertical section through the lock;

Figures 3 and 4 are cross sections, respectively, on the lines 3—3 and 4—4 of Figure 2;

Figure 5 is a plan view of a portion of the lock.

As illustrated in Figure 1, 1 is a vehicle door having an opening in its upper portion and a chamber in its lower portion for receiving the window 2 when lowered from a position closing the opening. 3 is a window regulator for raising and lowering the window and comprising the pivotal lifter arm 4, the crank 5 and suitable mechanism between the crank and the lifter arm for swinging the latter upon rotation of the former. This mechanism includes the rack 6, which is pivotally connected to the lifter arm, and the pinion 7 which meshes with the rack and is adapted to be driven from the crank 5.

The crank 5 is secured to the drive shaft 8 as by means of the pin 9 extending transversely through the hub of the crank and the drive shaft. This pin is secured from accidental disengagement by means of the escutcheon 10, which normally extends over the ends of the pin and is yieldably held in this position by the upholstery 11 located upon the inner side of the door frame and in the present instance the lock board 12. The drive shaft 8 is polygonal-shaped and is mill stock. The pinion 7 is preferably a stamping and is firmly secured between the

washer 13 and the annular flange 14 of the bearing member 15, both the washer and bearing member being also formed preferably of stampings. In the present instance the ends of the teeth of the pinion 7 extend laterally beyond the sides of this pinion and into corresponding recesses in the adjacent faces of the washer and bearing member so that the washer, pinion and bearing member rotate as a unit. The ends of the pinion teeth may be made to extend beyond the sides of the pinion by a coining operation.

The pinion 7 is in axial alignment with the drive shaft 8 and is driven therefrom by means of suitable irreversible drive mechanism located therebetween. This drive mechanism includes the hollow hub member 16, preferably formed of a stamping, which has the annular flange 17 rigidly secured to the outer end of the drive shaft and is provided with the opening 18 intermediate the ends of its cylindrical flange and the slot 19 of less width than the opening and leading from the opening longitudinally of the cylindrical flange to its outer end. 20 is a resilient coiled wire or coil spring surrounding the cylindrical flange of the hub member and having the inturned ends 21 and 22 which extend into the opening 18. 23 is a sleeve preferably formed of a stamping extending through and fixedly secured in the lock board 12 and surrounding the coiled wire 20 and adapted to be engaged by the convolutions of the same when expanded. 24 is a bearing member preferably formed of a stamping surrounding the inner end of the hub member 16 and having an axial portion 25 fitting upon the drive shaft 8 and a radial flange 26 located between the cylindrical flange of the hub member and the sleeve. This radial flange and the cylindrical flange 27 of the hub member 16 at the opposite end of the wire provide the space between the hub member and the sleeve for receiving the wire. 28 is a key member also preferably formed of a stamping and having a projection 28' which is adapted to pass through the slot 19 and lie within the opening 18 of the cylindrical flange of the hub member 16, at which time it is located between the inturned ends 21 and 22 of the wire. This key member has at its inner end the stub shaft 29 and at its outer end the rivet 30, the stub shaft extending axially

into and being journaled in the outer end of the drive shaft 8 and the rivet 30 extending axially through the pinion 7 and the washer 13 and having at its outer end the head 31 which cooperates with the shoulders 32 upon the key member to firmly secure the washer 13, pinion 7 and bearing member 15 together.

To hold the parts in operative relation and to form a unit thereby facilitating mounting, the sleeve 23 has at its outer end, the inturned flange 33 which abuts the outer face of the bearing member 15 and near its inner end the in-rolled bead 34 which is engageable with the radial flange 26 of the bearing member 24, whereby the bearing members are held from movement away from each other and consequently the wire, hub member, key member and associated parts are held in operative relation. The sleeve 23 is also provided near its outer end with the outwardly extending radial flange 35 which is preferably formed by crimping and which is adapted to abut the outer face of the lock board 12. The inner end of the sleeve is provided with the outwardly extending turned-over flange 36 which rests against the washer 37 at the inner side of the lock board, this washer being one of a number of washers of different thickness and selected to compensate for various thicknesses of the lock boards.

The radial flange 17 of the hub member 16 is fixedly secured to the drive shaft by reducing the outer end of the drive shaft and serrating this reduced portion and then forcing the same through the opening in the radial flange to form corresponding serrations therein. The outer end of the drive shaft is then turned over upon the radial flange to hold the latter from longitudinal displacement.

It will be seen that rotation of the crank 5 rotates the hub member 16 through the drive shaft 8 and one of the edges of the cylindrical flange of this hub member formed by the opening 18 engages one of the in-turned ends of the coiled wire to contract the latter and move its convolutions inwardly away from the sleeve 23. The inturned end is brought into engagement with the projection 28 upon the key member 28 and this rotates this key member and with it the pinion 7. The pinion being in mesh with the rack will thereby swing the lifter arm. This operation holds true regardless of the direction of rotation of the crank. However, with the power removed from the crank and power applied to the pinion 7 to rotate the same, this pinion will through the key member 28 and one of the inturned ends of the coiled wire expand the coiled wire to firmly engage the sleeve to thereby prevent rotation of the pinion.

65 From the above description it will be read-

ily seen that I have provided a lock which is so arranged and constructed that its parts may be formed of stampings or mill stock thereby reducing the cost of manufacture. It will also be seen that I have provided 70 a unitary construction including the irreversible drive mechanism or lock and the drive and driven members.

What I claim as my invention is:

1. The combination with a rotatable hub 75 member provided with an opening, of a sleeve surrounding said hub member, a wire between said hub member and sleeve having inturned ends extending into said opening, bearing members at opposite ends of said 80 wire and between said hub member and sleeve, a key member extending into said opening between the inturned ends of said wire and a driven member secured to said key member. 85

2. The combination with a rotatable drive shaft, of a driven member and irreversible drive mechanism between said drive shaft and driven member including a hub member fixed upon said drive shaft and provided with an opening, a sleeve surrounding and 90 rotatably supporting said hub member, a wire surrounding said hub member and located within and engageable with said sleeve, said wire having inturned ends engaging in said opening and a member secured to said driven member and extending into said opening and between the inturned ends of said wire. 95

3. The combination with a rotatable drive 100 shaft, of a driven member, a hub member rotatable with said drive shaft and provided with an opening, a sleeve surrounding said hub member, a wire between said hub member and sleeve having inturned ends 105 extending into said opening, bearing members at opposite ends of said wire and between said hub member and sleeve, a key member extending into said opening between the inturned ends of said wire and connected to said driven member and means upon said sleeve for holding said bearing members from movement away from each other. 110

4. The combination with a rotatable drive shaft, of a pinion adapted to be driven therefrom, a hollow hub member fixed upon said drive shaft and provided with an opening, a sleeve surrounding said hub member, a wire between said hub member and sleeve having inturned ends extending into said opening, bearing members at opposite ends of said wire and between said hub member and sleeve, a key member extending into said opening and rigidly secured to one of said bearing members and pinion, and means upon said sleeve for holding said bearing members from movement away from each other. 115 120

5. The combination with a rotatable drive shaft, of a driven member and irreversible 125 130

- drive mechanism between said drive shaft and driven member, including a key member having a portion journaled in said drive shaft and a rivet for rigidly securing said 5 driven member to said key member.
6. The combination with a rotatable drive shaft, of a pinion adapted to be driven from said drive shaft and irreversible drive mechanism between said pinion and drive shaft 10 including a hub member fixed upon said drive shaft and provided with an opening, a sleeve surrounding and rotatably supporting said hub member, a key member having a portion extending into said opening, 15 a portion journaled in said drive shaft and a rivet for rigidly securing said pinion to said key member, and a wire between said hub member and sleeve and having inturned ends extending into said opening on opposite 20 sides of said key member.
7. The combination with a rotatable drive member, of a driven member and irreversible drive mechanism between said members, including a sleeve forming a fixed part of said 25 irreversible drive mechanism and having in-
- tegral means spaced longitudinally thereof for securing said sleeve to a support.
8. The combination with a rotatable drive member, of a driven member and irreversible drive mechanism between said members, including a cylindrical hub having an inwardly extending radial flange forming an opening, said driving member having one end portion sleeved and extending through said hub opening and flared outwardly against 30 said flange for securing the hub to the driving member.
9. The combination with a rotatable drive member, of a driven member and irreversible drive mechanism between said members, including a sleeve forming a fixed part of said irreversible drive mechanism, a hub fixed upon said drive member within said sleeve, and a bearing having an axial portion 35 engaging said drive member, a radial portion 40 engaging said sleeve and a portion intermediate said aforesaid portions engaging said hub.

In testimony whereof I affix my signature.
STANLEY W. NICHOLSON.
